METHOD AND APPARATUS FOR ETCHING

Conrad Skladal, Jr., Dallas, Tex., assignor to Texas Instruments Incorporated, Dallas, Tex., a corporation of Delaware

Application September 3, 1953, Serial No. 378,337

16 Claims. (Cl. 41—9)

This invention relates to a method and apparatus for etching and more particularly, to an etching process as a result of which electrical circuits are printed, the printing being by the dissolution of portions of an electrically conductive sheet through the agency of a fluid capable of etching and apparatus for carrying out same.

An accepted standard technique for producing printed circuits originates with the step of bonding a sheet of copper of approximately .001 to .003 inch in thickness to a corrosion resistant plastic base. The copper, required to form the electrical circuit, is then covered by an enamel that is resistant to the fluid employed for the etching. When a printed circuit is thus prepared and is treated with a fluid capable of etching copper, the copper not coated with the enamel dissolves and the desired circuit is thereby produced. A fluid commonly used to etch copper is ferric chloride. With the proper process conditions copper is readily soluble in this fluid. Since the plastic base and the enamel are corrosion resistant, the coated copper is unaffected by the process and the desired circuit remains bonded to the plastic base.

As the printed circuit process above described depends upon the dissolution of copper in a ferric chloride solution, the equipment used must be corrosion resistant to ferric chloride to operate satisfactorily for any length of time. In one successful and satisfactory type of apparatus, a stone tub is used as the etching fluid container. A shaft extends through one wall of the tub and is driven by a motor located outside of the tube. A series of cup-shaped paddle wheels are mounted on the end of the shaft inside the tub and are either formed from rubber or covered with rubber. The portion of the drive shaft inside of the tub is also rubber covered. The circuit to be etched is suspended above the paddle wheels in a suitable location and as the shaft is turned by the motor, the etching fluid is thrown against the printed circuit and the copper unprotected by the enamel is dissolved. As stated, this apparatus produces very satisfactory printed circuits in a short time, but the initial cost of the equipment is high.

In another type of apparatus a glass tub is utilized as the container. Mechanical agitation of the etching fluid is provided by either a mechanical rocker system located externally of the tub or by a mechanical stirrer extending down into the fluid. Satisfactory plates are produced by this type of apparatus, but the time required to print each circuit varies from 60 to 80 minutes. In place of using the mechanical stirrer, a submerged header ring formed with a series of holes and connected outside of the glass tub to a source of air can be used. As air is supplied to the header, the etching fluid is agitated by the air from the header bubbling through the fluid. This type of apparatus is even more satisfactory since the time required to produce each plate is reduced to approximately 45 minutes.

Another type of apparatus uses a glass spray gun to aspirate the etching fluid against the surface of the article to be etched. Air under pressure supplied to the nozzle

2

of the spray gun picks up the etching fluid and sprays it against the surface of the circuit to be printed. Besides producing plates of a high quality, the use of the spray gun type of equipment further reduces the production time for each plate to about 10 to 15 minutes per plate.

It should be noted at this point that when using ferric chloride as the etching fluid, agitation is an essential step in the process due to the chemical reactions involved. The agitation introduces oxygen into the fluid which liberates free chlorine to combine with the copper and form copper chloride. Copper chloride is a soluble salt in acetic solutions and since ferric chloride is acetic to a certain extent, the copper chloride dissolves back into the etching fluid. In addition to liberating free chlorine from the solution, agitation also assists in removing the copper chloride from the surface of the plate as it forms and thus keeps a fresh copper surface exposed to the action of the free chlorine.

According to the present invention a novel apparatus and method are presented to cut down the production time for each plate appreciably without loss of quality. More specifically, this invention utilizes a nozzle or nozzles submerged in the etching and connected with a source of air. The nozzle or nozzles are provided with a venturi passage so that a reduction in the supply air pressure is converted into a corresponding increase in velocity. This stream of high velocity air on emerging from the nozzle carries a stream of etching fluid upward to strike against the surface of the prepared circuit suspended above the level of the fluid. It has been found that this stream of air does not produce turbulence in the fluid but draws the fluid instead from all sides in a streamlined flow to produce a steady stream of high velocity fluid. This streamlined flow appears to form "walls" which take the place of the outer jet of the usual ejector pump. Thus, besides acting to dissolve the copper surface, the stream of fluid tends to remove the copper surface by a scrubbing action not possible with the mist produced by the spray gun apparatus. A cover and seal are provided for each form of apparatus of the invention to prevent the loss of fluid and to trap fumes which would otherwise escape and corrode nearby objects.

Accordingly, it is a principal object of this invention to provide a method and apparatus for etching printed circuits that is simple, inexpensive in construction, and that will produce printed circuits in much less time than is possible with comparable equipment.

It is another object of this invention to provide an apparatus in which the arrangement can be varied to utilize a number of nozzles to reduce the etching time over that possible when using a single nozzle.

It is another object of this invention to provide a construction in which the fumes produced during the process are trapped and removed in a manner to eliminate the tendency to corrode nearby objects as well as to make working conditions more pleasant.

It is still a further object of this invention to provide an arrangement suitable for the continuous production of printed circuits.

Other and further objects of the present invention will appear from the following detailed description when taken in conjunction with the drawings in which:

Figure 1 is a view in vertical section of one form of the invention showing apparatus suitable for producing a single printed circuit that utilizes a single nozzle;

Figure 2 is a view in section through the nozzle showing the venturi passage;

Figure 3 is a view in plan showing an arrangement wherein more than one nozzle is used in the production of printed circuits;

Figure 4 is a view in section along line 4—4 of Figure 3;

Figure 5 is an exploded perspective view illustrating

an apparatus suitable for the continuous production of printed circuits;

Figure 6 is a view in section of the apparatus shown in Figure 5;

Figure 7 is a view in end elevation partly broken away of the apparatus shown in Figure 5; and

Figure 8 is a view in section showing the support for the plate circuit holders.

Referring now to the drawings, Figure 1 shows an apparatus suitable for producing a single printed circuit. The etching fluid is placed in a container which consists of a bottom 10, a cylindrical inner wall 11, and a cylindrical outer wall 12. The inner wall 11 of the container is considerably higher than the outer wall 12 and acts as a support for a lid 13. A series of rectangular areas 16 are formed around the upper circumference of wall 11 to provide spaced air outlets; consequently, lid 13 is actually supported by the portions of the wall 11 between the rectangular openings 16. The fluid container and its associated wall structure can be formed from a material corrosion resistant to the etching fluid as for example, glass or any suitable plastic such as polystyrene or an acrylic resin.

Lid 13 is a comparatively flat circular disc preferably made from a plastic material such as an acrylic resin that can be machined. Lid 13 is turned down in two successive steps from its original diameter to leave two annular areas designated respectively as 26 and 26a. A circular cylinder 15 is supported by lid 13 from the annular area 26 and in like manner, a circular cylinder 14 is supported by lid 13 from the annular area 26a. As shown, cylinder 15 is of considerably greater length than cylinder 14. When lid 13 is in place on the fluid container, inner wall 11 is positioned between the cylinders 14 and 15 and cylinder 15 extends downward and is located between inner wall 11 and outer wall 12 of the fluid container. The circuit to be etched, plate 33, is supported at the center of lid 13 by any suitable type of non-corrosive clips 34 and 35. Lid 13 is provided with a hole 25 to allow air inlet tube 19 to extend outward from the container.

A nozzle plate 17, constructed as shown in Figures 1 and 2, is essentially a rectangular plate and drilled with holes 23 and 24 to receive the air inlet tube 19 and nozzle 18, respectively. In the preferred construction, air inlet tube 19 and nozzle 18 form a force fit with holes 23 and 24. As an alternative threaded connection can be used. In the center of each hole 23 and 24 is a smaller diameter hole 23a and 22, respectively, that connects into either end of the main air passage 21. The main air passage 21 for this nozzle plate construction extends slightly past the mid-point along the length of the nozzle plate since only a single centrally located nozzle 18 is used.

The structure of the nozzle plate may take a form similar to that shown in Figures 3 and 4 when it is desired to use a plurality of nozzles in the etching process. In Figure 3, the nozzle plate 32 shown in plan is circular and mounts five rows of five nozzles each. It will be understood that the invention is not limited to this number or arrangement of nozzles since the arrangement can be varied as desired and is limited only by the ability to provide air passages to each nozzle. Using the same numbers in Figures 3 and 4 for the same parts or functions as used in Figures 1 and 2, Figure 4 shows air inlet tube 19 placed in a forced fit with a hole 23 drilled into plate 32. Hole 23 is connected with main air passage 21 by passage 23a of reduced diameter. Main air passage 21 extends sufficiently across plate 32 to allow a plurality of passages 22 to connect the nozzles 18 with passage 21. A series of enlarged holes 24 are drilled into nozzle plate 32 to receive the bases of nozzles 18. The rows of parallel nozzles on either side of the central row are provided with air by means of passages 33a drilled at right angles to the main air passage 21.

Regardless of whether a single nozzle or a plurality of

nozzles is used, the assembly and function of the apparatus of Figure 1 is the same. The nozzle plate is placed into the bottom of the fluid container with the air inlet tube 19 extending upward. The etching fluid is then placed in the container to some appropriate level such as indicated by the dotted line 27 but sufficient to submerge the nozzle or nozzles. Since there is no connecting passage between the areas enclosed by the circular inner wall 11 and that enclosed by the outer wall 12, the area between the walls 11 and 12 must be filled separately. This area can be filled with either the etching fluid or some other fluid such as water and to a level indicated by the dotted line 28. If the two areas should be interconnected, it is clear that both the inner and outer areas defined by walls 11 and 12 will be filled with the etching fluid. Lid 13 with the cylindrical skirts 14 and 15 is placed in position on the fluid container with the air inlet tube 19 extending through hole 25. Flexible tube 20 then fits over air inlet tube 19 and is connected to a source of compressed air.

As air is supplied to the nozzle or nozzles through tube 19 and passages 23a, 21 and 22, the high velocity air stream carries the etching fluid upward in a streamlined flow to impinge against etch plate 33. After striking against the plate, a large percentage of the etching fluid returns to the main body of the fluid, but a portion remains suspended in the air as fine particles. It is to be noted that cylinder 14 extends downward very close to but does not quite contact the surface of the fluid. Therefore, an air outlet passage 29 is provided which forces the air to travel in a path downward and through the area 29, upward between walls 11 and 14, out through the openings 16 and downward between walls 11 and 15. A portion of the fluid settles out of the air as it travels downward and through the area 29 and the remaining portion of the fluid is separated from the air by the fluid trap provided by the liquid between the walls 11 and 12 before reaching the atmosphere. Thus, the air baffle and seal combine to separate the etching fluid from the air and eliminate the noxious and corrosive fumes that would otherwise be present due to the etching process.

An apparatus similar to that of Figure 1 in principle, but adapted for continuous production of printed circuits is shown in Figures 5, 6 and 7. The apparatus consists of two principal assemblies as illustrated in the exploded perspective view of Figure 5. Discussing first the lower assembly of Figure 5, the fluid container is designated generally by the numeral 40 and is essentially a hollow rectangular box with a flat raised central portion 41 and a substantially deeper portion 42 and 43 at either end. The purpose of this type of arrangement will be discussed in a subsequent paragraph. The container can be formed of stainless steel, glass, rubber, or a polystyrene plastic. The plastic is the preferred material since it can be molded, cemented, or fastened together by means such as screws. The nozzle plate 44 is mounted on the raised central portion 41 of the container and mounts a plurality of nozzles 18. Air inlet tube 19 connects into the main air passage 21 drilled in nozzle plate 44 and forms a fluid tight connection with hole 45 in the raised portion 41 of container 40. The nozzles 18 fit into enlarged holes 24 drilled into nozzle plate 44 and are connected by passages 22 with the main air passage 21. It will be appreciated that there are several rows of nozzles 18 suitably connected with the main air passage 21.

The assembly designated generally by the numeral 39 forms the remaining portion of the apparatus for continuous production of printed circuits. The basic structure for assembly 39 consists of two side pieces 47 and 48 separated by and connected to a rectangular sheet 46 curved at either end so as to form an air tight inverted closure. Each of the side plates 47 and 48 is formed with two integral vertically extending projections at either end. A hole is drilled in each projection so that the

holes in corresponding projections on each side plate serve as bearings for a shaft supported by the projections.

Beginning at the upper left end of assembly 39 as viewed in Figures 5 and 6 as shown by the end view in Figure 7, shaft 57 is supported at one end by projection 49 of side plate 47 and at the other end by projection 53 of side plate 48. A pulley 58 is mounted on shaft 57 and fixed to rotate with the shaft by a key 59. A pulley 60 is mounted at the other end and fixed to rotate with shaft 57 by a key not shown. Shaft 57 extends beyond projection 53 and mounts a spur gear 61 which serves as the drive connection for the assembly. Vertically downward from shaft 57, projections 50 and 54 in side plates 47 and 48 respectively mount and support shaft 62. Pulleys 63 and 64 are positioned at either end of shaft 62 with pulley 63 in vertical alignment with pulley 58 on shaft 57 and similarly, pulley 64 with pulley 60. Unlike the pulleys on shaft 57, pulleys 63 and 64 are free to turn on shaft 62. In a corresponding construction, the upper projections 51 and 55 at the opposite end of side plates 47 and 48 respectively mount and support shaft 74 which in turn mounts two freely rotatable pulleys 75 and 76. Lower projections 52 and 56 mount and support shaft 71 with the two freely rotatable pulleys 72 and 73 mounted on shaft 71.

Each of the side plates carries two stub shafts located on a line approximately at the mid-point between the shafts carried by the vertically extending projections but offset at either end a required amount from a vertical line between the shafts. Side plate 48 carries stub shafts 65a and 68a which mount pulleys 66 and 69 respectively. Side plate 47 carries the stub shafts 65b and 68b and stub shaft 65b mounts pulley 67, but the pulley mounted on stub shaft 68b is not shown in any view. Although no shown, the side plates are sufficiently reinforced at the stub shaft mounting points to carry any side thrusts or loads imposed on the shafts.

It can be seen from the foregoing description that the stub shafts and the identical sides of assembly 39 allow the use of two identical continuous rubber belts 77 and 78 in the conveyor system. Belt 77 is placed first around stub shaft pulleys 66 and 69 and is then brought downward and placed around pulleys 63 and 72 and finally upward and around pulleys 58 and 75. Similarly, belt 78 is placed around stub shaft pulley 67 and the pulley not shown and then in succession around pulleys 64 and 73 and pulleys 60 and 76. The conveyor system is completed by placing a series of plate supports 79 in between the two belts 77 and 78. For this purpose, the continuous belts are drilled with appropriately spaced holes to receive pins 82 and 83 extending from the end of each printed circuit support 79 as shown in Figure 8. Assembly 39 is supported from the upper edge of container 40 by cleats 85 and 86 fixed to side wall 47 and by cleat 87 shown and a similar cleat not shown fixed to side wall 48.

Container 40 is filled with the etching fluid to a level above the nozzles 18 as indicated by the dotted line 84. Assembly 39 is then placed in container 40 and supported by the cleats 85, 86, 87 and a similar cleat not shown. The lower edge of the inverted closure formed by the rectangular plate 46 and the side plates 47 and 48 extends below the fluid level and, as referred to above, the inverted closure forms a fluid trap to separate the particles of etching fluid contained in the air. The printed circuits 81 are then placed in the slots 80 extending across the width of the plate supports 79 which provide a convenient and simple means for inserting and removing plates in the process of continuous production. As spur gear 61 is driven by a motor at the proper speed, the pulleys 58 and 60 rotate the belts 77 and 78 with their attendant plate supports 79 and printed circuits 81 as a unit while the remainder of the conveyor system rotatably supports and guides the printed circuits past the

nozzles 18 and in a path to assist in trapping the particles of etching fluid contained in the exhaust air stream.

It will be noted that in Figure 6 the printed circuits 81 are carried at an angle to the direction of the etching fluid stream as produced by the high velocity air through nozzles 18. When the printed circuits are carried in a horizontal position a problem arises in connection with the use of multiple nozzles for etching. This problem is due to the fact that a stream of fluid upon striking a flat surface perpendicular to the fluid stream spreads out in all directions, so, when the streams of fluids from two or more nozzles meet, a point of zero velocity fluid movement is reached and the rate of etching decreases sharply. By tilting the plate at a slight angle to the horizontal, these points of zero fluid velocity are eliminated and a fast rate of etch is provided. By means of the present invention, it is possible to etch a circuit 4 inches by 5 inches in approximately 3 minutes with a single nozzle as compared with a time of 10 to 15 minutes for equipment similar to that of the invention. The etching time can be even further reduced by the use of multiple nozzles in the invention to approximately 1½ minutes.

Although the method and apparatus of the present invention have been described in specific embodiments, nevertheless various changes and modifications obvious to one skilled in the art are within the spirit, contemplation and the scope of this invention.

What is claimed is:

1. Apparatus for continuously etching articles that comprises means defining a completely enclosed space over an etching fluid, means to continuously introduce a plurality of articles to be etched through a fluid seal and to withdraw continuously the etched articles through a fluid seal, and means for projecting said etching fluid in streams of high velocity against said articles.
2. Apparatus for etching that comprises an open container adapted to hold etching fluid, a member cooperating with said container adapted to define a completely enclosed space over fluid held in said container and a path for gas to escape from said enclosed space, said path leading through fluid held in said container, wherein particles of etching fluid contained in said gas are removed, a nozzle mounted in said container below the level of etching fluid when same is in said container, means to supply gas under pressure to said nozzle whereby to produce a steady stream of high velocity fluid, and means to hold an article to be etched within said enclosed space in a position to be acted upon by said fluid stream.
3. Apparatus for etching that comprises an open container adapted to hold etching fluid, a lid for said container adapted to cooperate with said container to form therewith a fluid seal wherein particles of etching fluid contained in a gas are removed and to define a completely enclosed space over fluid held in said container, a nozzle mounted in said container below the level of etching fluid when same is in said container, means to supply gas under pressure to said nozzle and means to hold an article to be etched within said enclosed space.
4. Apparatus as defined in claim 2 wherein a plurality of nozzles are provided.
5. Apparatus for etching that comprises an open container adapted to hold etching fluid having a circular bottom, an outer wall, and an inner wall having a slot 65 therein to allow gas to pass therethrough, a lid for said container having a circular top, an outer wall that depends between the outer and inner walls of said container to a point below the level of etching fluid when same is in said container, and an inner wall that depends within 70 said inner wall of said container and a point above the level of etching fluid when same is in said container, said container and lid being thus arranged to define a completely enclosed space over fluid held in said container and to establish a gas path from within said enclosed space to outside that passes through a fluid seal formed by the

outer wall of said lid and the inner and outer walls of said container, a nozzle mounted on the bottom of said container, means to supply gas under pressure to said nozzle, and means to hold an article to be etched within said enclosed space.

6. Apparatus for continuously etching articles that comprises a container having a raised central portion adapted to hold etching fluid, a cover means spaced from the ends of said container and cooperating therewith to define a completely enclosed space over fluid held in said container, means to convey articles to be etched between said cover means and one end of said container, through said fluid at said end of said container, into said enclosed space, through said fluid at the other end of said container and between said cover means and said other end of said container, and means to cause said fluid to etch said articles while they are passing through said enclosed space.

7. Apparatus as defined in claim 6 wherein said means to etch said articles includes a nozzle located on said raised central portion and means are provided to supply said nozzle with gas under pressure.

8. Apparatus as defined in claim 6 wherein said means to convey articles includes two belts, and article holding means are connected between said belts.

9. Apparatus as defined in claim 6 wherein said means to etch includes a plurality of nozzles located on said raised central portion, means are provided to supply said nozzles with gas under pressure, and said means to convey includes means to hold said articles at an angle as they are passed through said enclosed space.

10. A method for continually etching articles that comprises successively feeding articles to be etched adjacent a body of etching fluid, leading a stream of compressed gas to a nozzle within said body of etching fluid above which each said articles passes, and causing said etching fluid to flow under the influence of said gas through said nozzle in a steady stream of high velocity against each said article as it passes said nozzle above said body of etching fluid to etch same.

11. A method for continually etching articles that comprises successively feeding articles to be etched adjacent a body of etching fluid, leading compressed gas to a plurality of nozzles within said body of etching fluid above which each said article passes, and cause said etching fluid to flow under the influence of said compressed gas through said nozzles in a plurality of steady streams of high velocity against each said article as it passes said plurality of nozzles above said body of etching fluid to etch same.

12. A method as defined in claim 10 wherein said gas is subsequently led through a liquid trap to purify same before exhausting.

13. A method as defined in claim 11 wherein said articles to be etched are fed at an angle relative to said body of etching fluid.

14. The method for etching an article that comprises positioning an article to be etched above a body of etching fluid, leading a stream of compressed gas to a nozzle within said body of etching fluid, and causing said etching fluid to flow under the influence of said compressed gas through said nozzle in a steady stream of high velocity against said article to etch same.

15. The method defined in claim 14 wherein said compressed gas is led to a plurality of nozzles within said body of etching fluid.

16. The method as defined in claim 14 which includes the further step of subsequently leading said gas through a liquid trap to purify same before exhausting.
